UNITED STATES PATENT OFFICE.

CHARLES H. RIPPL, OF CLEVELAND, OHIO, ASSIGNOR TO THE ELECTRIC CONTROLLER & MANUFACTURING COMPANY, OF CLEVELAND, OHIO, A CORPORATION OF OHIO.

ELECTROMAGNET.

1,292,650.

Specification of Letters Patent. Patented Jan. 28, 1919.

Application filed June 20, 1917. Serial No. 175,722.

To all whom it may concern:

Be it known that I, CHARLES H. RIPPL, a citizen of the United States, residing at Cleveland, in the county of Cuyahoga and State of Ohio, have invented new and useful Improvements in Electromagnets, of which the following is a specification.

This invention relates to electromagnets, and particularly to electromagnets immersed in oil or to electromagnets in which the magnetic pole faces or like parts are lubricated with oil.

When an electromagnet immersed in oil is energized and the armature or other movable part thereof moves into contact with the core or other stationary part of the magnet structure, the oil between the contacting parts is expelled and the parts come into intimate contact.

When the magnet is deenergized, and the armature or other movable part thereof tends to move away from the stationary part, the intimacy of the contact causes the parts to stick together for a period of time which varies according to conditions which will be mentioned hereinafter. The contact surface at which the sticking occurs may be the actual working magnetic pole face of the armature or core, or it may be some other relatively flat stop surface on the structure. This action is found also in magnets surrounded by air, in which the pole faces or stop surfaces are lubricated with oil.

This tendency to stick temporarily appears to be caused as follows: When the magnet is deenergized and the movable part begins to move away from the stationary part, the space which forms between the separating parts fills with oil. The rapidity with which the surfaces move apart is determined by the rapidity of the flow of oil into the space between the surfaces. If the parts tend to move apart more rapidly a vacuum forms and the movement is retarded. After the surfaces have moved apart a considerable distance, for example, an eighth of an inch, the oil surrounding the magnet can flow freely into the space between the surfaces and the movement of the parts is no longer retarded and they move freely to full open position. The time period, then, during which the parts move imperceptibly and remain to all practical purposes in full closed position, and during

which they may be said to stick together, is determined by the perimeter and area of the contact surfaces. The time period is directly proportional to the area of the contact surfaces, because, if the surfaces are increased, the volume of oil which must flow in between them for any given amount of movement, and, hence, the time required for it to flow, will be proportionately increased; and the time period is inversely proportional to the perimeter of the surface contact, because the larger this perimeter, the shorter the time required for a given volume of oil to flow into the space between the surfaces. It will be apparent that the greater the viscosity of the oil in any case, the longer will be the time period. If the magnet is surrounded by air, instead of by oil, and if the contact surfaces are lubricated with oil, the action will be similar to that described above, the presence of the oil preventing the surrounding air from flowing into the space between the contact surfaces at a greater rate than the viscosity of the oil will permit.

In magnets having small contact area, the time period required for the magnet to open is negligibly small because the perimeter is relatively large with respect to the contact area. In larger magnets the ratio between the perimeter and the area is smaller and the time period required is therefore greater. In magnets having rectangular equilateral contact surfaces, the perimeter is proportional to the square root of the contact area, and in rectangular contact areas of other shapes, the perimeter is proportional to even smaller roots of contact area. In large magnets the time period may be reduced sufficiently for practical purposes, or made negligibly small, by dividing up the contact area into smaller areas and by providing communicating passages from the oil surrounding the magnet, whereby the surrounding oil will have access to each subdivision of the contact area.

The principal object of this invention, therefore, is to provide an electromagnet having oil-lubricated contact surfaces, in which the contact surface area is divided up into smaller areas, the perimeter of each of which communicates directly, or by a passageway, with the surrounding air or oil or other medium, whereby the time period of opening caused by the presence of the

lubricating oil may be made negligibly small.

Other objects will be apparent.

Referring to the accompanying drawing,

5 Figure 1 is a view partly in section and partly in elevation, of an oil-filled tank containing an electromagnetic apparatus employing my invention; Fig. 2 is a front elevation of the core or stationary member of

10 the oil-immersed electromagnet shown in Fig. 1, and drawn to a larger scale; Fig. 3, is a side elevation of the magnet core shown in Fig. 2; Fig. 4 is a view similar to Fig. 3, partly broken away, and showing a mag-

15 net core of larger size; and Figs. 5 and 6 are views corresponding to Figs. 2 and 3, respectively, showing a modification of my invention, and drawn to a smaller scale.

Referring to Fig. 1, I have shown the

20 apparatus container or tank 1, containing oil or other liquid 2. Immersed in the oil is the electric or other apparatus 3, comprising the frame 7, and the alternating current magnet 8. The magnet 8 has the 25 stationary U-shaped core 4 fastened to the frame 7 at 5; the energizing winding 6 on the lower leg of the core 4; the armature 9 pivoted to the frame 7 at 10; and, on the upper leg of the core 4, the dephasing ring 30 11 embedded in the groove 13 in the pole face 12 of the core.

The particular type of magnet and apparatus shown form no part of my invention; but in Fig. 1, I have illustrated the 35 magnet and apparatus fully shown and described in Stratton's Patent, No. 1,225,686, granted May 8, 1917.

The operation of that part of the apparatus involving my invention may be described as follows: When the winding 6 is energized with alternating current, the armature 9 is attracted toward the stationary core 4, and the upper end of the armature is brought into engagement with the 45 pole face 12 of the core, the shading ring 11 producing at this pole a continuous pull in a manner well understood. When the winding 6 is deenergized, it sometimes occurs that the oil in which the magnet is 50 immersed flows into the space between the contact surfaces of the armature 9 and the pole face 12 so slowly that the armature is not released in the normal manner, but temporarily sticks or remains temporarily in 55 the closed position.

I have found that if the contact area between the armature and the pole face is less than a certain maximum, this sticking or delay in opening will not occur, or the 60 time period thereof will be negligibly small. In order, therefore, to prevent sticking in all cases and in all sizes of magnets, I preferably provide grooves 14 in the face of the pole 9, which divide up the pole face 65 into sections. These grooves not only re-

duce the contact area of any one section to or below the area at which sticking is negligible, but also provide channels by means of which the oil surrounding the magnet may have easy access to the entire perimeter of each of the contact surface sections. In the magnet shown in Figs. 1, 2, and 3, the groove 13, containing the ring 11, may serve as one of the non-stick grooves, so that only one additional non-stick groove 14 is needed. 70 I prefer to place these grooves in the magnet face 12 in a transverse direction with respect to the edges of the laminations. In Fig. 4, which illustrates the core of a larger magnet, three grooves 14 are required in 80 addition to the groove 13 containing the dephasing ring 11.

I have found by experiment that a magnet having contact surfaces measuring $2\frac{1}{2}'' \times 2\frac{3}{4}''$, with an average smoothness of contact surface, and with oil having the viscosity of No. 32 transformer oil, satisfactory results are obtained by locating the grooves 14 transversely of the laminations, as above described, and on center lines about $\frac{1}{2}$ inch 90 apart. I find also that grooves $\frac{1}{16}$ of an inch deep and $\frac{1}{16}$ of an inch wide are satisfactory.

By locating the grooves transversely with respect to the lamination edges, and by making them of the size mentioned, it is possible to form the grooves in the individual stampings when they are stamped from sheet metal, which obviates the necessity of cutting them in the magnet after it is assembled. It will, however, be apparent that the grooves may be of other sizes and run in other directions from those which I have shown, the essential feature of my invention when carried out by the employment of 105 grooves, as above described, being that the grooves are arranged to communicate between the interior of the contact surfaces and the oil surrounding the contact surfaces, whereby the oil may have easy access not 110 only from the outside toward the center of the surfaces by way of the perimeter of the surfaces as a whole, but also from the center toward the outside of the surfaces by way of the additional virtual perimeter provided by the grooves. 115

The grooves, instead of being placed in the pole face of the stationary core, as I have shown and described them, may be placed in the face of the movable armature; 120 or, if it be desirable to stop the movement of the armature toward the core upon stop surfaces other than the actual pole faces of the magnet, then the grooves may be placed in such stop surfaces.

In Figs. 5 and 6 I have shown a modification of my invention, in which a channel 15 is provided, running through the body of the magnet and terminating in an orifice approximately at the center of that part 125

of the contact surface inclosed by the de-phasing ring 11. This magnet is approximately of the same size as that shown in Figs. 2 and 3, though drawn to a smaller scale, and it will therefore be apparent that by employing the channel 15 I have divided up the contact surface into a ring, and have increased the virtual perimeter of the surface whereby the surrounding oil will have easy access to the contact surfaces.

While I have shown and described my invention as applied to an electromagnet immersed in oil, it will be understood that my invention is applicable in every respect to an electromagnet surrounded by air but in which the pole faces or other relatively flat contact surfaces are lubricated with oil. Also, while I have shown and described an alternating current electromagnet, it will be apparent that my invention is applicable in every respect to direct current electromagnets.

My invention is not limited to the exact shapes, locations, directions or dimensions of the grooves or channels which I have disclosed, and many changes and modifications other than those shown or mentioned above may be made without departing from the spirit of my invention.

30 I claim—

1. A pair of wet smooth surfaces adapted to be brought into mutual contact one of them being divided into sections by one or more channels communicating with a fluid whereby the time required to separate said surfaces is sensibly reduced.

2. In an electromagnet, an energizing winding, two relatively movable members adapted to be moved into contact with each other on certain wet smooth contact surfaces

when the magnet is energized, one of the surfaces being divided into sections by one or more channels communicating with a surrounding fluid medium whereby the time required to separate the said members is 45 sensibly reduced.

3. In an electromagnet, a magnetic circuit, an energizing winding therefor, a stationary and a movable member for the circuit, wet smooth pole faces on the members, the 50 movable member being adapted to be attracted toward the stationary member to bring the pole faces into engagement with each other when the winding is energized, and a sufficient number of grooves in one 55 of the pole faces communicating with a surrounding fluid medium, whereby the time required to separate the pole faces is reduced a predetermined amount.

4. In an electromagnet, an energizing 60 winding, two relatively movable members adapted to be moved into contact with each other on certain wet smooth contact surfaces when the magnet is energized, and a sufficient number of channels communicating 65 with one of the surfaces and with a surrounding fluid medium, whereby the time required to separate the said members is sensibly reduced.

5. An oil container, a switch having mutually engageable smooth surfaces in the oil, and one or more channels communicating with one of the surfaces and the oil and dividing the same into sufficiently small areas to reduce the time required to separate the 75 surfaces a predetermined amount.

Signed at Cleveland, Ohio, this 15th day of June, 1917.

CHARLES H. RIPPL.
